SUCTION CLEANER BRUSH

Eugene F. Martinet, Cleveland, Ohio, assignor to
 The P. A. Geier Company, Cleveland, Ohio, a
 corporation of Ohio

Application April 4, 1936, Serial No. 72,762

5 Claims. (C. 15-8)

The invention relates to brushes for suction cleaners, and more particularly to a rotary brush construction journalled in the suction nozzle of an electrically operated, portable, domestic or household, suction cleaner; and the present invention utilizes certain of the inventions claimed in my copending Patent 2,072,956, filed October 6, 1933, entitled Suction cleaner brushes, and constitutes improvements upon the construction 10 shown in said Patent 2,072,956.

A suction cleaner is frequently provided with a motor driven brush journalled in its nozzle when the same is used for general household cleaning purposes. It is, however, desirable, in such a 15 cleaner brush construction, to have the brush adjustable with respect to the nozzle; so that the position of the periphery of the brush may be changed relative to the plane of the nozzle lips, to compensate for bristle wear, or to enable different surfaces, having different characteristics to 20 be most efficiently cleaned.

However, in rotary brush constructions for suction cleaners, whether adjustably mounted or not, certain problems are always present. First, 25 dust and dirt particles passing through the nozzle always have a tendency to find their way to and collect upon the bearings for the brush, causing inefficient cleaner operation. Second, hair, threads, string and the like which are picked 30 up by the brush have a tendency to wind up on the brush and in so doing frequently bind between the rotating and non-rotating parts of the brush bearings; thus retarding or stopping rotation of the brush and causing inefficient cleaner operation. 35 Third, vibration incident to the end journaling of a center driven rotary brush in a suction cleaner nozzle tends to increase the noise made when operating a motor driven suction cleaner.

The first two problems are overcome in a satisfactory manner by the construction shown in 40 said Patent 2,072,956. However, the present improvements not only overcome the first two problems in a more satisfactory manner, but also 45 eliminate the third problem.

Accordingly, it is an object of the present invention to provide a driven, preferably adjustable, rotary brush construction for a suction cleaner with means substantially preventing dust 50 and dirt particles from collecting in and about the bearings therefor.

It is a further object of the present invention to provide a driven, preferably adjustable, rotary brush construction for a suction cleaner with 55 means preventing the collection or binding of hair,

threads, string and the like between the rotating and non-rotating parts of the brush bearings.

Moreover, it is an object of the present invention to provide a driven, preferably adjustable, rotary brush construction for a suction cleaner 5 with a silently operating brush mounting.

And finally, it is an object of the present invention to provide a driven, preferably adjustable, rotary brush construction for a suction cleaner which incorporates the foregoing objectives in 10 simple, compact and inexpensive manner, easy to operate, adjust or repair.

These and other objects are attained by the present improvements comprising suction cleaner brush constructions, parts, elements, devices, instruments, and combinations, a preferred embodiment of which is shown in the accompanying drawing and is hereinafter described in detail, and which improvements are hereinafter claimed, and which may be stated in general terms 20 as preferably including in suction cleaner brush construction, a rotary brush, means preferably adjustingly mounting the brush in the nozzle of a cleaner, the mounting means including rotating parts on the brush and non-rotating parts on the 25 nozzle, said parts forming telescoping rotating and non-rotating annular channels, one of said parts being preferably formed of rubber or other resilient or vibration dampening material, one of 30 said non-rotating parts preferably lapping over the end of the brush, and a shield preferably spanning the nozzle opposite to said overlapping part.

In the drawing:

Figure 1 is a fragmentary side elevation of a 35 portion of an electrically-operated, portable suction cleaner equipped with the improved brush construction;

Fig. 2 is a section through the nozzle and portions of the brush, taken on the line 2-2, Fig. 1; 40

Fig. 3 is a bottom plan view of the parts shown in Fig. 2;

Fig. 4 is an enlarged fragmentary sectional view 45 similar to Fig. 2, showing the improved brush construction;

Fig. 5 is a transverse section thereof, taken on the line 5-5, Fig. 4; and

Fig. 6 is an other section taken on the line 6-6, 50 Fig. 4.

Similar numerals refer to similar parts throughout the various figures of the drawing.

A usual type of electrically operated portable suction cleaner is shown in Fig. 1, which may comprise a motor in a motor housing 1, provided with a fan housing 8, having a fan (not shown) 55

therein, and a suction nozzle 9 communicating with the fan housing. An operating handle 10, and a dust bag 11 connected with the exhaust opening of the fan housing also are provided for the cleaner; and the motor housing 7, the fan housing 8, and nozzle 9, are mounted on front casters 12 and preferably an adjustable double rear caster 13, for ambulant motion over a floor or the like indicated at 14. The cleaner may also be provided with a lighting device generally indicated at 15.

The brush nozzle includes walls forming a tubular neck 16 which leads to the fan chamber, and an elongated brush housing suction mouth 17. The improved rotary brush is generally indicated at 18, is provided with bristles 19, and is detachably or removably and adjustably rotatably mounted in the suction mouth 17.

The brush 18 is preferably motor driven, as shown in the drawing, and to accomplish the same, an endless preferably flat band rubber belt 20 passes over the brush pulley surface 21 and the end 22 of the motor shaft.

The bearing construction for removably and adjustably mounting the rotary brush 18 in the brush housing nozzle mouth 17, is best shown in Figs. 2, 3, 4 and 5. The brush member 18 preferably includes a main shaft 23, made preferably of wood, and terminating at each end in a reduced boss 24. A cup-shaped ferrule 25 is tightly fitted over each boss 24 for preventing the ends of the wooden shaft 23 from splitting; and an axial hole 26 is provided in each end of the shaft 23, and through the adjacent ferrule 25, into which an axle pin 27 is driven to make a tight fit.

A bearing block 28, substantially square in cross section as best shown in Fig. 5, is journalled on each pin 27 by a bore 29, which is preferably eccentrically located through each block; and the blocks 28 are retained on the axle pins 27 abutting the adjacent ferrules 25 by split rings 30 mounted on the outer end of each pin.

An annular hub cap 31, having a preferably squared closed end shank 32, is mounted on and encloses each block 28 so as to enclose the outer end of each axle pin 27; and the squared shank of each hub cap 31 is preferably eccentrically located with relation to the remainder of the hub cap to correspond with the eccentric location of the bore 29 through the block 28. Each hub cap 31 terminates in an annular flange portion 33, which surrounds and overlaps the reduced boss 24 and the ferrule 25 thereon, at each end of the brush shaft 23.

From the pulley portion 21 extending to each end of the brush shaft 23 there is also provided a preferably tubular metal sleeve 34; and the outer flange-like end 35 of each sleeve 34 extends beyond, is spaced from and overlaps the boss 24, the ferrule 25, and the adjacent hub cap flange 33, and terminates in an outturned peripheral flange 36, as best shown in Fig. 4.

A mounting cap 37 formed of rubber or other resilient or vibration dampening material, is provided with a squared, tubular shank 38, and is slipped over the squared shank 32 of the hub cap 31. The mounting cap 37 is also provided with an annular flange portion 39, which overlaps the flange 36 of the tubular sleeve 34.

Thus, an annular channel 40 is formed between the spaced annular flange members 33 and 39, of the caps 31 and 37, respectively; and an annular channel 41 is also formed at each end of the brush 18 between the bosses 24 and the sleeve

member ends 35. The brush parts or members 23, 24, 25, 27, 30 and 34 are rotating parts having an annular channel 41 formed therein; and the parts 23, 31 and 37 are non-rotating parts or members having an annular channel 40 formed therein. Accordingly, the rotating sleeve member 35-36 is telescoped within the non-rotating channel 40, and the non-rotating flange member 33 is telescoped within the rotating annular channel 41.

A preferably integral brush mounting clip 42, preferably U-shaped in cross section, as best shown in Fig. 5, and having spring retaining fingers 43, is rigidly mounted by rivets 44 on each inner end of the brush housing nozzle mouth 17; and each U-shaped spring-fingered clip 42 forms substantially three sides of a square as shown in Fig. 5, for receiving the squared shanks 38 of the mounting caps 37 for holding the same and the hub caps 31 and blocks 28 therein, in non-rotative position in the cleaner nozzle.

A nozzle lip plate 45 is also mounted on the nozzle 17, as best shown in Figs. 3 and 6; and the end bars 46 thereof are preferably arcuately formed at 47 and spaced from the ends of the nozzle 17 (Fig. 6) and provide shields spanning the nozzle opposite to the places where the mounting cap flanges 39 overlap the sleeve flanges 36.

When the brush 18 is mounted in the nozzle 17, as shown in the drawing, the blocks 28, the hub caps 31, and the mounting caps 37 are maintained stationary with respect to the nozzle walls by the clips 42; and the brush parts or members 23, 24, 25, 30, 34, 35 and 36 rotate, because the axle pins 27 mounted in the bores 29 are journalled in the blocks 28, when the brush is rotated by the belt 20 when the cleaner motor is operated.

By releasing the belt 20 from the shaft 22, and removing the nozzle lip plate 45, the brush 18 may be readily removed from the nozzle. Likewise, due to the eccentricity of the blocks 28 and the caps 31 and 37 thereon, the mounting caps 37 may be inserted into the clip 42 in any one of four positions, which will locate the brush selectively at different levels with respect to the plane of the nozzle lips; and in this manner bristle wear may be compensated for, and particular characteristics of the surface being cleaned may be accommodated.

The particular arrangement of the inter-telescoping rotating and non-rotating parts 35-36, 33 and 39 and the channels 40 and 41 formed thereby effectively shields and seals the brush bearings against the collection of dust, dirt and the like.

Likewise, by locating the non-rotating preferably resilient cap member flanges 39 in positions overlapping the outturned flanges 36 on the ends 35 of the rotating brush parts 34, hair, threads, string and the like is prevented, in wrapping around the brush upon rotation thereof from entering and jamming or binding between the rotating and non-rotating parts.

Moreover, by providing the shield bars 46-47 overlapping the flanges 39 which telescope over the flanged ends 35-36 of the brush members 34, the prevention of a collection of hair, threads, string and the like to bind between rotating and non-rotating parts is further increased.

Also, by providing the mounting caps 37, by forming the same of rubber or other resilient or vibration dampening material, and by mounting the same in the spring clips 42, the rotating brush always operates silently and does not in-

crease the noise made incident to the operation of the cleaner motor.

And finally, the improved brush construction for a suction cleaner may be operated, adjusted, replaced or repaired quickly and easily by any person and is very efficient in operation and readily fabricated.

Having now described the features of the invention, the construction, adjustment and use of the preferred form of improved suction cleaner brush construction, and the advantages obtained thereby; the new and useful parts, elements, devices, combinations and constructions, and reasonable mechanical equivalents thereof obvious to those skilled in the art, are set forth in the appended claims.

I claim:

1. In a suction cleaner including a nozzle and a rotary brush, means at each end of the brush 20 removably mounting the brush within the nozzle including a rotatable annular member on each end of the brush terminating in an outturned peripheral flange, a resilient vibration dampening non-rotatable mounting member held by the nozzle having an annular flange at each end of the brush overlapping said outturned flange, and a shield spanning the nozzle at each end thereof opposite to said overlapping flanges.
2. In a suction cleaner including a nozzle and 30 a rotary brush, means at each end of the brush removably mounting the brush within the nozzle including an annular flange forming an annular channel in the end of the brush, a bearing block journaling the brush at each end, a hub 35 cap mounted on the bearing block and having an annular flange extending into said channel, a resilient vibration dampening mounting cap on said hub cap removably mounted in the nozzle and having a flange forming with said hub cap flange a second annular channel, and said brush flange extending into said second channel and said mounting cap flange overlapping said brush flange.

3. In a suction cleaner including a nozzle and a rotary brush, means at each end of the brush 5 removably mounting the brush within the nozzle including a rotatable annular flange forming an annular channel in the end of the brush and terminating in an outturned peripheral flange, a bearing block journaling the brush at each end, a hub cap mounted on the bearing block and having an annular flange extending into said channel, a resilient vibration dampening mounting cap 10 on said hub cap removably mounted in the nozzle and having a non-rotatable flange forming with said hub cap flange a second annular channel, said brush flange extending into said second channel, said mounting cap flange overlapping 15 said outturned flange, and a shield spanning the nozzle at each end thereof opposite to said overlapping flanges.

4. In a suction cleaner including a nozzle and a rotary brush, means at each end of the brush 20 mounting the brush within the nozzle including a rotatable annular member on each end of the brush terminating in an outturned peripheral flange, a non-rotatable annular flange held by the nozzle at each end of the brush overlapping said 25 outturned flange, and a bar spanning the nozzle adjacent to, but spaced from each end thereof opposite to said overlapped flanges.

5. In a suction cleaner including a nozzle and a rotary brush, means at each end of the brush 30 removably mounting the brush within the nozzle including a rotatable annular member on each end of the brush terminating in an outturned peripheral flange, a resilient non-rotatable annular flange removably held by the nozzle at each 35 end of the brush overlapping said outturned flange, and a bar having an arcuate formation therein spanning the nozzle adjacent to, but spaced from each end thereof opposite to said overlapped flanges.

EUGENE F. MARTINET. 40
